Attorneys.

UNITED STATES PATENT OFFICE.

WILLIAM S. ASHTON, OF WATERTOWN, MASSACHUSETTS, ASSIGNOR TO HOOD RUBBER COMPANY, OF WATERTOWN, MASSACHUSETTS, A CORPORATION OF MASSACHUSETTS.

BOOT-TREE OR LAST.

Application filed February 17, 1927. Serial No. 168,984.

My said invention relates to improvements in boot trees or lasts of the type used for manufacturing rubber boots and the like.

These are customarily made of metal having

- 5 a separable toe piece to facilitate removal of the last from the completed boot, the leg and toe portions having abutting faces which lie in intersecting planes, one of which is disposed substantially lengthwise of the last
- 10 and the other substantially perpendicular thereto, forming a substantially L shaped joint.

The invention aims to provide such a tree or last of exceedingly simple and durable construction in which the toe section is secured to the leg section by a connection permitting a limited sliding movement relative thereto when removal is desired, but preventing total disconnection whereby the toe section

20 is withdrawn with the leg section.

The invention further aims to provide a connection between the parts which will permit a pivotal movement of the toe section relative to the leg section to facilitate removal,

The invention further aims to provide simple and efficient means for holding the parts with their abutting faces pressed into intimate contact which means may be automatically disengaged by a pull upon the leg section and as readily engaged by reverse movement.

In order that the invention may be more readily understood reference is made to the 35 accompanying drawings in which:—

Figure 1 is a side elevation of what I at present consider the preferred embodiment of the invention, the lower part being shown in section.

40 Fig. 2 is a similar view showing the parts in the position assumed when being withdrawn from a boot.

Fig. 3 is a section on line 3—3 of Fig. 1.

Fig. 4 is a bottom view of the last.

45 Referring by reference characters to this drawing the numeral 1 designates the main or leg section of the tree or last and 2 the toe section, these having abutting faces disposed in intersecting planes indicated at A and B, the former as is customary being arranged substantially lengthwise of the leg portion and the latter being substantially perpendicular thereto or transverse to the

leg section, and the sections being preferably made of hollow aluminum castings for 55 lightness.

To effect a limited sliding connection between the parts I provide one of them, say the toe section 2 with a slotted guide (3) which projects into a guide way in the 60 abutting face of the other part. In the embodiment shown the guide way is formed by merely providing a slot in the face 1^a of the leg portion (as by cutting).

The guide 3 preferably comprises a pair 65 of parallel steel plates 3 riveted to a flange formation 2^a on the face 2^a of the toe section, which plates are preferably connected at the top by a cross member 3^a (preferably integral) to carry the retaining spring 5 hereinafter described.

The guide way is continued through the sole portion or bottom of the last and said bottom is provided with slots to receive the projecting portions of the plates 3. Said 75 plates 3 are provided with elongated slots 3^b disposed parallel to the face 2^a through which passes a cross member or pin 4 which is rigidly carried by the leg section near the lower end thereof and parallel to the face 1^a. 80 By reason of this pin and slot connection the toe section is capable of being moved down from the position shown in Fig. 1 to the limit determined by the closed upper ends of the slots, which movement takes place 85 when the leg section is pulled out of the completed boot.

To permit the toe tip to rock or incline downwardly when the pin reaches the upper of the slots the rear edges of the plates 3 90 are provided with cut away portions or notches 3^c and the upper ends of the slots are enlarged rearwardly as indicated at 3^d.

To hold the parts in closed position I provide spring detent means which preferably 95 takes the form of a leaf spring 5 having one end riveted or otherwise secured to the cross member 3^a from which it inclines downwardly and forwardly to a point where it is provided with a bend 5^a and a rearwardly 100 deflected end 5^b. Said spring cooperates with a cross member or pin 6 rigidly carried by the leg portion of the last just above plane B, and reference to Fig. 1 will clearly show how, with the parts in this position, 105 the toe section will be held firmly in place

by the pressure of the spring on the pin reacting on the upper end of guide 3. Pull upon the boot section, however, will cause the spring to yield and pin 6 to ride over the rounded portion or nose 5^a of the spring, and the reverse action will take place on closing of the last.

I claim:

1. A boot tree or last comprising a leg section and a toe section having faces abutting along intersecting planes, interengaging means effecting a limited sliding connection between said parts along one of said intersecting planes, including means for permitting the toe section to have a swinging movement about an axis parallel to said intersecting planes at the extremity of its sliding movement in one direction.
2. A boot tree or last comprising a leg section and a toe section having faces abutting along intersecting planes, one of which is disposed substantially lengthwise of the tree, a slotted guide carried by one of said sections and projecting from the lengthwise face thereof, the abutting face of the other section having a guide way to receive said guide, and a transverse pin passing through said slotted guide, the slot in said slotted guide having the major part thereof parallel to said lengthwise face and the remainder offset therefrom.
3. A boot tree or last comprising a leg section and a toe section having faces abutting along intersecting planes, interengaging means effecting a limited sliding connection between said parts along one of said intersecting planes, including means for permitting the toe section to have a swinging movement about an axis parallel to said intersecting planes, and means for releasably holding the abutting faces of the leg and toe sections in intimate contact.
4. A boot tree or last comprising leg and toe sections having faces abutting along in-

tersecting planes which are substantially lengthwise and transverse to the leg section respectively, a slotted guide projecting from the lengthwise face of the toe section, the lengthwise face of the leg section having a guide way receiving said slotted guide, a cross member carried by said leg section near its lower end and engaging said slotted guide, said slotted guide being exteriorly recessed adjacent its upper end.

5. A boot tree or last comprising leg and toe sections having faces abutting along intersecting planes which are substantially lengthwise and transverse to the leg section respectively, a slotted guide projecting from the lengthwise face of the toe section, the lengthwise face of the leg section having a guide way receiving said slotted guide, a cross member carried by said leg section near its lower end and engaging said slotted guide, the guide slot of said slotted guide being, at the upper end, extended laterally towards the rear of the last.

6. A boot tree or last comprising a leg section and a toe section having faces abutting along intersecting planes which are substantially lengthwise and transverse to the last respectively, a slotted guide carried by the lengthwise face of the toe section and comprising a pair of spaced parallel slotted plates, the lengthwise face of the leg section having a guide way to receive said guide plates, a cross member carried by the leg section adjacent its lower end and passing through the slots in said plates, said guide plates extending above the transverse face of the toe section, a leaf spring carried by the extended portion of said guide plates and having reversely inclined portions, and an abutment carried by the leg section for cooperating with said spring.

In testimony whereof, I affix my signature.

WILLIAM S. ASHTON.
